UNITED STATES PATENT OFFICE.

ELMER W. GIBBS, OF CANTON, OHIO, ASSIGNOR TO THE GIBBS MANUFACTURING COMPANY, OF CANTON, OHIO, A CORPORATION OF OHIO.

TOP.

Application filed February 17, 1926. Serial No. 88,759.

- The invention relates to the construction of tops and twisting heads for the same and is an improvement upon the type of tops shown in Letters Patent No. 847,933 issued to me March 19, 1907, Letters Patent No. 1,005,020 issued to me on October 3, 1911 and Reissue No. 15,475 issued to me on October 24, 1922; and the improvements include changes in the proportions and shape 10 of the top body to cause the same to spin more steadily and for a greater length of time, and changes in the head which permit the same to be twisted and held more easily by the hand.
- 15 The objects of the improvement are to construct a top body and twisting head of sheet metal in which the body of the top is of greater diameter and less depth than in my former patents above referred to, lowering the center of gravity and causing the top to spin more steadily; and to improve and simplify the construction of the twisting head, forming the same of substantially mushroom shape to permit it to be easily 20 grasped by the thumb and fingers for twisting and by the fingers for releasing the top therefrom by pressure of the thumb.
- An embodiment of the invention is illustrated in the accompanying drawing, in 25 which
- Figure 1 is a perspective view of a top body and twisting head embodying the invention;
- Fig. 2, a vertical sectional view of the same;
- Fig. 3, a perspective view of the twisting head;
- Fig. 4, a detached perspective view of the upper flanged disk of the twisting head;
- 40 Fig. 5, a similar view of the spring barrel, and
- Fig. 6, a detached perspective enlarged view of the lower flanged disk of the twisting head.
- 45 Similar numerals of reference indicate corresponding parts throughout the drawing.
- The twisting head is composed of the spring barrel 1, the upper flanged disk 2 and the lower flanged disk 3, connected to the opposite ends of the spring barrel as by the lugs 4 extended through slots and notches 5 and 6 in the upper and lower disks, respectively, and clinched upon the same.
- 50 The spring barrel thus forms the stem 55
- portion of the twisting head and is of considerably less diameter than the disks at the ends thereof, permitting the same to be easily grasped between the fingers of one hand, the disks preventing the fingers from slipping over either end of the head.
- The upper disk 2 has a depending peripheral flange 7, preferably knurled or roughened as shown, to afford a firm grasp upon the same when twisting the head to 60 place the spring 8 under tension.
- The spring is in the form of a coil of substantially the length of the spring barrel the upper end thereof being hooked as at 9 and extending through a notch 10 in the upper end of the barrel while the lower end of the spring protrudes beneath the lower end of the barrel and terminates in the downturned end 11.
- The lower disk 3 may be provided with a 70 depending peripheral flange 12 upon which are formed at intervals the depending teeth 13, each having one vertical edge 14 and one inclined edge 15.
- The depending flange is preferably bent 75 inward and thence downward under the rim of the disk to avoid a protrusion of the teeth; and the ends of the teeth are preferably rounded, to avoid a cutting of the fingers.
- 80 It is evident that by this construction and arrangement of the parts a better and more efficient twisting head is produced than those disclosed in my prior patents above referred to, as the spring barrel forms the 85 stem portion of the twisting head dispensing with the outer casing shown in the prior patents referred to.
- The twisting head thus formed is of such 90 shape that it may be easily grasped by the fingers of one hand to twist the same and received between two fingers of one hand in order that the top may be released from the head by pressing downward upon the stem thereof with the thumb. The upper flanged 95 disk prevents the fingers from slipping from the twisting head as the top is released therefrom. A simple but substantial twisting head is thus made which is well adapted to the purpose of spinning the top, which operation will be later described.
- The top comprises the upper and lower 100 slightly concaved members 16 and 17 respectively which are of greater diameter and less depth or concavity than the dome 105
- 110

shaped members forming the tops in my prior patents. The members 16 and 17 are connected together by means of the rabbet and lip flanges 18 and 19 respectively formed upon the adjoining edges of the two sections.

The upper section 16 is provided with the raised portion 20 which receives the disk 21 forming an air chamber 22 between the disk and the top of the raised portion 20, a practically air tight joint being produced between the disk and the inner surface of the top, thus cutting off the inflow of air into the interior of the top. The upper surface 16 of the raised portion 20 is provided with the apertures or sockets 23 and with the curved indentations or slots 24, inclined tongues 25 being located in said slots.

The stem 26, which extends from above 20 the upper top member downward to the lower top member, is preferably formed of sheet metal of cylindrical form, the upper end thereof having cusps 27 formed thereon, which are bent as shown in the drawings 25 forming an upper rounded closed end for the stem.

The lower end of the stem rests within the socket 28 formed in the lower member of the top, the head of the spindle 29 being received 30 within said lower end of the stem, thereby centering the same. An integral flange 30 may be formed upon the spindle, and bears against the bottom wall of the socket 28. The disk 21 is mounted upon the stem and its peripheral edge is held in tight engagement with the inner wall of the upper section 16 by means of the annular rib 31 formed upon the stem. For the purpose of producing a humming top, the hollow section 40 35 40 is provided with the apertures 32.

In the top shown in my prior patents, the body portion, formed of the two dome shaped sections, had a diameter of three inches and a total depth of one and one-half inches from 45 the point of the spindle, while in the present top, the diameter is three and one-half inches and the total depth from the point of the spindle is one inch. The stem extends about an inch and three-eighths above the body in 50 both cases, thus locating the center of gravity considerably lower in the improved top.

Thus the diameter of the body in accordance with previous practice was substantially twice the depth of the body, while in the 55 present improvement the diameter of the body is substantially three times the depth thereof.

It will be obvious that by forming the top body of these large sections which have less

concavity than those shown in my prior patents above referred to, the center of gravity of the top is brought closer to the spindle and the top will be caused to spin more steadily.

The operation of the top may be briefly 60 described as follows: The stem 26 is inserted, from the lower end upward through the hollow section of the twisting spring as best shown in Fig. 2, and the projecting end 11 on the lower end of the spring is engaged 70 with one of the apertures or sockets 23 in the upper surface of the top.

The head is then rotated, by grasping the disk head between the thumb and fingers, in which operation the teeth 13 successively 75 enter and engage as ratchets in the inclined recesses 24, the resilience of the spring 8 and the inclined edges 15 of the teeth permitting the teeth to ride over the intervening upper surface of the top.

When the spring has been sufficiently 80 twisted, the top is spun as by holding the barrel stem 1 of the head between the index and middle fingers of one hand and pressing the stem downward with the thumb, which 85 serves to disengage the teeth 13 from the top and permits the twisting spring to unwind itself, in doing which it rapidly rotates the top with the stem thereof as an axle in the twisting spring, until the depending 90 end 11 of the spring is disengaged from the top recess after which the head is lifted from the stem of the top or the stem of the top drops out of the head.

I claim:

1. In combination with a spinning top having a stem and a body portion thereon, said body portion having an aperture and a series of indentations in its upper side, a twisting head including a spring barrel, a 100 disk permanently attached at each end of the barrel, a peripheral flange upon the upper disk, a toothed flange upon the lower disk for engagement with said indentations, and a twisting spring in the barrel connected 105 thereto at its upper end, the lower end of the spring being received in said aperture.

2. A twisting head for tops including a spring barrel stem, an annular flange fixed to each end of the stem, a peripheral flange 110 upon the upper flange and teeth upon the lower flange, and a twisting spring located within the barrel stem and connected to one end thereof.

In testimony that I claim the above, I 115 have hereunto subscribed my name.

ELMER W. GIBBS.
